ROLL HOLDER

Francis J. Moore, Minneapolis, Minn.

Application April 20, 1939, Serial No. 268,936

4 Claims. (Cl. 242—55.5)

My present invention relates to holders for rolls of paper webs intended for general use, but especially well adapted for holding rolls of toilet paper.

5 It is an object of this invention to provide a roll holder that will prevent the spinning of a roll by a quick pull on the free end portion thereof and thereby unwind therefrom more paper than is required resulting in extravagance and waste. 10 A further object of the invention is to provide a roll holder on which a roll of paper may be quickly and easily mounted. A still further object of the invention is to provide a holder for a roll of paper that is extremely simple, of relatively small cost to manufacture and that is rugged in construction and with only a single moving part. A further object of the invention is to provide a roll holder that is easy to keep clean and that has a neat and pleasing appearance.

20 To the above end, generally stated, the invention consists of the novel construction and arrangement of parts hereinafter described and defined in the claims.

25 In the accompanying drawing, which illustrates the invention, like characters indicate like parts throughout the several views.

Referring to the drawing:

Fig. 1 is a view in end elevation showing my improved roll holder on which is mounted a roll of toilet paper;

Fig. 2 is a front elevation of the same with some parts broken away and sectioned and with other parts shown by means of broken lines;

35 Fig. 3 is a plan view of the roll holder with the roll of toilet paper removed therefrom;

Fig. 4 is a fragmentary view partly in plan and partly in section taken on the line 4—4 of Fig. 2;

Fig. 5 is a fragmentary view partly in front elevation and partly in section taken on the irregular line 5—5 of Fig. 1;

Fig. 6 is a fragmentary detail view partly in side elevation and partly in section taken on the line 6—6 or Fig. 5;

45 Fig. 7 is a fragmentary view partly in plan and partly in section taken on the line 7—7 of Fig. 2; and

Fig. 8 is a fragmentary detail view partly in side elevation and partly in section taken on the line 8—8 of Fig. 4.

The letter A indicates a roll of toilet paper wound on a paper cylinder or core B.

The improved holder, in part, is formed from a single round rod folded upon itself to form in part, at its folded end, an upright wall bracket

9 the members of which are in downwardly diverging relation. The members of the rod, at the lower end of the wall bracket 9, are bent horizontally forward in outwardly diverging relation to afford a pair of supporting arms 10. At the outer ends of the arms 10 the members of the rod are bent upwardly to afford a pair of upright parallel prongs 11.

The wall bracket further includes a face plate 12 having a rearwardly extended marginal flange 13. This face plate 12 and its flange 13 covers the bracket section 9 formed by the rod. The base of the wall bracket is horizontal and the sides thereof are in upwardly converging relation and meet in a relatively sharp point at the top of the wall bracket. The face plate 12 and its flange 13 are brazed to the bracket section 9 and the space back of the face plate 12 and above the wall bracket section 9, is filled with metal as indicated at 14.

The wall bracket 9—12 is secured to a wall X by a pair of screws Y which extend through holes Z in said wall bracket. At the lower ends of the prongs 11 is a roll support or rest 15 in the form of a cross-tie member which connects said prongs and holds the same properly spaced. This roll support 15 is made of a quarter round bar the flat side of which is uppermost and has in its end portions holes through which the prongs 11 project. The roll support 15 rests on the arms 10 and is rigidly secured thereto and to the prongs 11 by brazing or otherwise. It will be noted that the longitudinal edges of the roll support 15 are relatively sharp.

The roll of toilet paper A rests on the support 15 between the prongs 11 and is free to turn on a follower member 16 which loosely extends axially through the paper core B.

The follower member 16, is, as shown, a bar that is rectangular in cross-section. This bar 16 is held by the prongs 11 for raising or lowering movements and which prongs loosely extend through bores 17 in the bar 16. This bar 16 loosely rests on the internal bottom of the paper core B and its greatest width is materially less than the internal diameter of said core.

As the diameter of the roll A diminishes, by the unwinding of the paper thereon, the follower bar 16 slides downwardly on the prongs 11, under the action of gravity and continues to rest on the core B.

During the turning of the roll A about the follower bar 16, by pulling on the free end portion of the paper web to unwind a section of the same from the roll, said roll is moved with frictional

- contact transversely on the flat upper face of the supporting bar 15. Also, during the turning of the roll about the follower bar 16 said bar is supported on the lower internal surface of the core B. 5 Obviously, the movement of the turning of the roll A on the supporting bar 15 and the contact of the internal surface of the core B with the follower bar produces sufficient drag or friction to prevent the spinning of the roll A.
- 10 As the paper is unwound from the roll A sections may be torn therefrom on the customary weakened tearing line formed therein or sections may be torn therefrom on the sharp front longitudinal edge of the support 15.
- 15 The drawing illustrates a commercial form of the invention, but it will be understood that the same is capable of certain modifications as to details of construction, arrangement and combination of parts within the scope of the invention 20 herein disclosed.

What I claim is:

1. A device of the kind described formed in part from a single rod folded upon itself to afford at its folded end, a wall bracket, the members of 25 the rod at the wall bracket being bent to afford a pair of forwardly projecting arms, the members of the rod being again bent at the outer ends of

the arms to afford a pair of upright prongs, a roll supporting member connecting the members of the rod at the lower ends of the prongs, and a follower member extending loosely through the core of a paper roll resting on the supporting member and mounted on the prongs for raising and lowering movements, said supporting member and the follower member each being positively held against rotation. 5

2. The structure defined in claim 1 in which the 10 supporting member is a cross-tie bar having in its end portions holes through which the prongs project, said bar being rigidly secured to the members of the rod.

3. The structure defined in claim 1 in which the 15 supporting member is a cross-tie bar having in its end portions holes through which the prongs project, said bar being rigidly secured to the members of the rod and the front upper longitudinal edge of the supporting member being relatively 20 sharp.

4. The structure defined in claim 1 in which the 25 follower member is a bar having in its end portions holes through which the prongs loosely project.

FRANCIS J. MOORE.
